(54) **LOCK, PERCUSSION, SIDE, FOR RIFLES**

(76) Inventor: **Elisha Strong**

*Clylsta Strong, a citizen of
Letters Patent.*

The Schedule referred to in these Letters Patent and making part of the same, containing a description in the words of the said Clylsta Strong, himself of his improvement in making Rifle Locks, called the Percussion Side Lock.

To all to whom these presents shall come:—
Be it known that I, Clylsta Strong of Marion, in the County of
Guauga, & State of Ohio, have invented a new and useful improve-
ment in making locks, & that the following is a full & exact
description of said lock, called the Percussion Side Lock for
cups or kernels, made use of for Rifles, Pistols, & all kinds of fire arms.
The plate is shaped like a flint lock, except the part with a mortice
through the head apart lengthways of the plate, long enough to contain the
cock, dog & dog spring. The cock is little bent in the middle, & the
fore part turned up to make flat to place the thumb against, so
as to cock the same, and the hind part wide enough to pass through
the mortice, so that the main spring may rest upon it back of the
pin. The main spring is straight, put on with a screw on the fore
part of the plate on the inside, with a pin in the mortice to hold
it in place. The dog is almost straight, but large enough at the end
outside of the plate to receive a notch to hold the lock when cocked;
the cock notch will be on the cock outside of the plate, and a set
screw in the same. The dog screw is secured on back of the mortice
the fore part passing tho' the mortice by bending so that the
small end will press against the dog above the pin; there
must be a screw or pin through the cock and dog in the
fore part of the plate; there may be a half cock notch if desired to
have a roll in the cock for the main spring likewise. The punch
or exploding pin must be inserted in the fore end of the cock.

Right

high enough to clear the plate, for if there must be a screw or pin in the end large enough next the barrel to receive a hole sufficient to cover it except the cylinders in the barrel are made for each in the usual way.

As witness Claridon Aug 5th 1801
